UNITED STATES PATENT OFFICE

CHARLES W. GORDON, OF PLEASANTVILLE, NEW YORK, ASSIGNOR TO THE SUPER-HEATER COMPANY, OF NEW YORK, N. Y.

TUBE SHEET

Application filed January 4, 1929. Serial No. 330,179.

My invention relates to tube sheets of the type employed in heat exchange structures, and has particular reference to elements of this character to which collectors or headers are directly secured.

The invention is particularly applicable to surface or non-contact heat exchangers of the tubular multiple-pass type, and in the accompanying drawings forming a part hereof I have illustrated the invention as applied to a locomotive type feedwater heater, although it is to be understood that the invention is equally well applicable to other types of apparatus.

Fig. 1 is generally a vertical longitudinal section through a locomotive type feed water heater, the right half being a true section, the left half showing the shell in section and the parts within the shell partly in elevation and partly in central vertical section; Fig. 2 is an end elevation looking from the right of Fig. 1; and Figs. 3 and 4 are plan and elevational views respectively of the improved form of tube sheet employed.

Referring now to Fig. 1, the heater comprises a cylindrical casing 1 closed at one end by tube sheet 2 and at the other end by the cap or cover plate 3. A plurality of tubes 4 are expanded at one end into tube holes 5 in tube sheet 2, which, as will be evident from Fig. 3, are divided into a number of spaced groups for a purpose which will become clear later.

At their other ends, tubes 4 are expanded into semi-circular tube sheets 6 and 7, these tube sheets being separated diametrically along the plane of the paper in Fig. 1 and freely movable with respect to each other and the casing 1 to allow for expansion of the tubes 4. As viewed in Fig. 1 the curved front edge of the tube sheet 6 is seen, while the part of 7 which is seen is the straight vertical edge. The semi-circular headers 8 and 9 are secured respectively to the outer faces of semi-circular tube sheets 6 and 7. Of these headers, the upper part of the figure shows the front rounded surface of the front header, and at the lower part of the figure the vertical flat surface of the rear header is seen.

The fixed tube sheet 2 has bolted to its outer

face a semi-circular header 10 and a pair of quarter-circular headers 11 and 12, header 11 being provided with an inlet connection 13 and header 12 being provided with a similar outlet connection 14.

As previously noted, the semi-circular headers 8 and 9 are bolted to tube sheets 6 and 7 with the line of division vertical, while as shown more clearly in Fig. 2 the line of division between header 10 and headers 11 and 12 is horizontal and the line of division between headers 11 and 12 is vertical.

With this arrangement of the headers it will be readily apparent that four passes through the bundle of tubes 4 are provided. Assuming the inlet to be through connection 13, the first pass is through the group of tubes covered by header 11, thence upwardly through semi-circular header 8, back through the tubes connecting the upper end of header 8 with the left-hand side of header 10, thence through header 10 and the tubes covered by the right half thereof to the upper end of header 9, downwardly through header 9 and finally back through the tubes connecting the lower end of header 9 with the quarter-header 12.

Inlets 15 are provided in casing 1 for the admission of steam or other heating medium, and a drain 16 is provided for the removal of condensate.

The structure so far described is not novel, and prior to my invention considerable difficulty has been encountered in maintaining a joint between tube sheet 2 and the headers secured thereto which would remain tight under a fluid pressure of high magnitude such as that encountered when the heater is located between a boiler feed pump and the boiler. For this particular class of service a metal to metal joint has been found more satisfactory than any known form of packed or gasket joint, and in the heretofore best known practice the outer face of tube sheet 2 is finished to an accurate plane surface, as are the bottoms of the headers to be secured thereto, and the headers and tube sheet assembled by direct bolting of the headers to the tube sheet without the use of any gasket or packing at the joint.

Experience has shown, however, that while a single header may be satisfactorily bolted to a tube sheet as, for example the bolting of headers 8 and 9 to the tube sheets 6 and 7 and a tight joint maintained, leakage occurs if it is attempted to bolt a plurality of headers to a single integral tube sheet. Taking the header and tube sheet assembly shown in Fig. 2 for example, the header 10 can be bolted to the tube sheet and a tight joint maintained as long as the adjacent headers 11 and 12 are not bolted to the tube sheet, but upon the latter being bolted to the tube sheet and drawn to a tight seat, the header 10 will almost invariably develop leaks at points 10^a and 10^b which cannot be eliminated even by the application of the utmost permissible pressure to the header through drawing up of the bolts securing it to the tube sheet.

Although I do not desire to be in any way bound by such theory, it is my belief that this leakage is caused by the fact that the bolting of headers 11 and 12 to the face of the tube sheet sets up therein a fibre stress which is transmitted through the tube sheet in a manner which distorts the latter and results in a non-plane surface under the semi-circular header 10. The latter is necessarily extremely stiff in order to withstand the internal pressure exerted thereon in service, and its form, moreover, is such that it is extremely rigid so that it cannot be distorted by pressure applied through the securing bolts sufficiently to make it follow a non-plane tube sheet surface.

I have successfully overcome the difficulty due to the above phenomenon by providing a rabbeted groove 17 in the outer face of the tube sheet between the half header 10 and the quarter headers 11 and 12. The depth of this groove may vary between wide limits with respect to the thickness of the tube sheet depending upon the service under which the tube sheet is operated, the maximum depth of the groove being determined by the thickness of metal between the bottom of the groove and the inner face of the tube sheet (as represented by 17^a) necessary to withstand the service pressure within the casing. 1. The minimum depth of groove required is determined by the character of the metal from which the tube sheet is made, but in the case of the usual steel tube sheet, the depth of the groove is preferably at least one-third of the thickness of the tube sheet.

While in the preferred form illustrated I have shown a groove of rectangular section, it will be obvious that the invention can be carried into effect by the use of grooves of other sectional form.

A second groove 18 is preferably provided between the quarter-headers 11 and 12 for the purpose of preventing the transmission of fibre stress from the surface under any one header from being transmitted to the surface

under any other header, as I have found by experience that the most satisfactory results are obtained if each individual header secured to a given tube sheet is separated by means of a groove in the face of the tube sheet from all other headers secured thereto. 70

It is to be understood, however, that such separation of each header from all other headers secured to the same tube sheet is not in all cases necessary to secure the desired object of the invention, and it is further to be understood that the invention is in no way limited to the form of apparatus chosen herein for illustrative purposes but may be applied equally well to any form of apparatus where a plurality of headers are secured to an integral tube sheet. 75 80

I claim:

1. As a new article of manufacture, a tube sheet provided with a plurality of spaced groups of tube holes and a groove in one face of the tube sheet located between and separating two of the groups of tube holes. 85

2. As a new article of manufacture, a tube sheet provided with a generally circular group of tube holes spaced along a diameter of the circle to form separated generally semi-circular tube groups and a groove in one face of the tube sheet along the diametral space between said tube grooves. 90 95

3. As a new article of manufacture, an integral metallic tube sheet provided with three spaced groups of tube holes, one of said groups being generally semi-circular in outline with the other two of said groups being generally quarter-circular in outline, and a groove in one face of the header located on the diameter of the tube sheet separating the semi-circular group of tube holes from the quarter-circular groups of tube holes. 100 105

4. As a new article of manufacture, an integral metallic tube sheet provided with three spaced groups of tube holes, one of said groups being generally semi-circular in outline with the other two of said groups being generally quarter-circular in outline, a groove in one face of the header located on the diameter of the tube sheet separating the semi-circular group of tube holes from the quarter circular groups of tube holes, and a groove in the same face of the header located on the radius separating the quarter circular groups of tubes. 110 115

5. In apparatus of the class described, a plane metallic tube sheet, a plurality of spaced groups of tubes secured therein, a plurality of headers secured to one face of said tube sheet, and a groove in the face of the tube sheet to which the headers are secured, said groove lying between and separating two of said headers. 120 125

6. In apparatus of the class described, a tube sheet, headers bolted to one face of said tube sheet and grooves in the face of the tube sheet to which the headers are bolted, said 130

grooves being located so that each header is separated by a groove from each of the other headers.

7. In apparatus of the class described, a tube sheet having a plane face, two headers bolted to said face, each of said headers having a straight wall relatively closely spaced from and substantially parallel to a corresponding wall of the other header, and a straight groove cut in said face between said walls.

8. In apparatus of the class described, a tube sheet having a plane face, three headers bolted to said face, each of said headers having a straight wall relatively closely spaced from and substantially parallel to a straight wall of each of the remaining headers, and straight grooves cut in said face between each pair of adjacent header walls.
